[57] CLAIM

The ornamental design for a multiple dispenser for liquid soap, shampoo, lotion, and the like, as shown and described.

DESCRIPTION

FIG. 1 is a top, front, and left side perspective view of a multiple dispenser for liquid soap, shampoo, and the like showing our new design;

FIG. 2 is a top, front, and right side perspective view of an alternate embodiment thereof, the only difference residing in the width of the article;

FIG. 3 is a front elevational view of the embodiment of FIG. 1;

FIG. 4 is a right side elevational view of the embodiment of FIG. 1;

FIG. 5 is a top plan view of the embodiment of FIG. 1;

FIG. 6 is a rear elevational view of the embodiment of FIG. 1; and

FIG. 7 is a bottom plan view of the embodiment of FIG. 1.

FIG. 1

FIG. 3
